DESIGN FOR A LAMP STAND

James E. Thodos, Chicago, Ill., assignor to Bend-a-Lite Plastics Division, branch of Oxygen Equipment & Service Co., Chicago, Ill., a corporation of Illinois

Application September 7, 1945, Serial No. 121,906

Term of patent 3½ years

(Cl. D48—20)

To all whom it may concern:

Be it known that I, James E. Thodos, a citizen of the United States, residing at Chicago, in the county of Cook and State of Illinois, have invented a new, original, and ornamental Design for a Lamp Stand, of which the following is a specification, reference being had to the accompanying drawing, forming a part thereof.

In the drawing:

Fig. 1 is a front elevational view of a lamp stand embodying my new design;

Fig. 2 is a side elevational view thereof; and
Fig. 3 is a sectional view on line 3—3 of Fig. 1, looking in the direction of the arrows.

The dominant features of my design reside in the portions shown in full lines.

I claim:

The ornamental design for a lamp stand, as shown and described.

JAMES E. THODOS.
